CHEST

William Joseph Carr, Gardner, Mass., assignor to Heywood-Wakefield Company, Gardner, Mass., a corporation of Massachusetts

Filed Mar. 25, 1964, Ser. No. 79,187

Term of patent 14 years

(Cl. D33—6)

FIG.3

FIG. 1 is a front view in perspective of the chest, the back of said chest being plain and unornamented;

FIG. 2 is a side elevational view taken from the left of FIG. 1, the other side of said chest being the same in appearance as the side illustrated; and

FIG. 3 is a plan view.

I claim:

The ornamental design for a chest, as shown and described.
